UNITED STATES PATENT OFFICE.

ALBERT R. PRITCHARD, OF ROCHESTER, NEW YORK, ASSIGNOR TO REED MANUFACTURING COMPANY, OF NEWARK, NEW YORK, A CORPORATION OF NEW YORK.

SPRAYER.

1,116,733.

Specification of Letters Patent. Patented Nov. 10, 1914.

Application filed March 16, 1911. Serial No. 614,947.

To all whom it may concern:

Be it known that I, ALBERT R. PRITCHARD, a citizen of the United States, and resident of Rochester, in the county of Monroe and State of New York, have invented certain new and useful Improvements in Sprayers, of which the following is a specification.

This invention relates to devices for spraying liquid insecticide, and other substances, by means of air-blasts.

The object of the invention is to produce a simple, durable and inexpensive device of the kind in question, particularly as relates to the construction of the tubes by which the liquid is conveyed to the air-blasts.

To this end the invention consists in the construction hereinafter described, as it is defined in the succeeding claim.

In the accompanying drawings:—Figure 1 is a front end-elevation of a sprayer embodying the present invention; and Fig. 2 is a horizontal section, on the line 2—2 in Fig. 1, of the forward extremity of the sprayer.

The invention is illustrated as embodied in a hand sprayer of any ordinary or suitable general form. This sprayer may comprise the usual air-pump, of which only the forward extremity of the cylinder 3 is shown in the drawings. The forward end of the pump-cylinder is closed by a conical sheet-metal member 4, which is provided with two blast-openings 5, as shown in Fig. 1, the arrangement producing two divergent air-blasts. Beneath the air-pump is suspended the usual liquid-receptacle 6, of which the forward end is closed by a screw-cap 7.

The present invention resides particularly in the two tubes 8 by which liquid is conveyed from the liquid receptacle to the air-blast openings 5. These two tubes pass through the screw-cap 7 from the interior of the receptacle, and their upper ends ter-

minate adjacent the blast-openings, as shown in Fig. 1. The tubes are supported in upright position by the conical mouth 9 of the sprayer, as they pass through this mouth and are soldered thereto. The upper portions of the tubes project for some distance above the lower wall of the part 9, and in order to support these portions of the tubes they are connected by a sheet-metal web 10. As shown in Fig. 2, this web is integral with the tubes 8, the latter being formed by rolling over the lateral margins of the same piece of sheet-metal of which the web is formed, and soldering the edges. The lower portions of the tubes are formed by downward continuations of the sheet-metal, rolled into tube form and soldered along their edges. This construction of the tubes integral with the web 10 is simple, inexpensive and strong, and the web supports the tubes rigidly in proper relation to the blast openings, and prevents them from being bent out of position when accidentally struck.

I claim:—

A sprayer having, in combination with a liquid receptacle and an air-pump with a conical sheet-metal mouth and with two widely-separated divergent air-blast orifices located within the mouth; an integral sheet-metal member comprising two tubes, formed by rolling over the sheet-metal, and a web connecting the upper ends of the tubes, said upper ends projecting upwardly to points adjacent the air-blast orifices and said web extending downwardly to, but terminating at, the conical mouth, while the tubes extend through said mouth and downwardly into the liquid-receptacle.

ALBERT R. PRITCHARD.
